BY J. Edward Maybee

ATTY.

UNITED STATES PATENT OFFICE.

EDWARD DEVINE RANCK, OF TORONTO, ONTARIO, CANADA, ASSIGNOR TO THE COLEMAN LAMP CO., OF WICHITA, KANSAS.

LIQUID-DISPENSING CAN.

Application filed October 13, 1923. Serial No. 668,421.

To all whom it may concern:

Be it known that I, EDWARD DEVINE RANCK, of the city of Toronto, in the county of York, Province of Ontario, Canada, a citizen of the United States of America, have invented certain new and useful Improvements in Liquid-Dispensing Cans, of which the following is a specification.

This invention relates particularly to containers for liquid fuels, lubricating oils and the like from which the contents may be poured as required and my object is to devise a container which cannot inadvertently be overfilled, which will pour without gurgling, from which, with one tilting of the can only a predetermined quantity can be poured, which will enable the user to stop the flow at will when the container is in pouring position, with which there is sufficient delay in the flow of liquid from the spout to enable the latter to be inserted in a receptacle without danger of spilling, and generally to make the container safe and convenient for use.

I attain my objects by means of the constructions hereinafter described and illustrated in the accompanying drawings in which—

Fig. 1 is a vertical section of my improved can in upright position;

Fig. 2 a similar view showing the can tilted to horizontal position; and

Fig. 3 a plan view of the can, partly broken away.

1 is a closed cylinder forming the body of the can. This is divided by a transverse partition 2 into two compartments 3 and 4. The lower compartment 4 is given the predetermined proportion to the upper compartment 3. For example, if the total capacity of the can be one gallon, the lower compartment may have a capacity of one quart and the upper a capacity of three quarts.

Through the upper end of the can extends a filling tube 5, which extends down within the upper compartment, so that the maximum liquid level in the can cannot rise above the lower end of the tube as the upper end of the can is otherwise entirely closed. The advantage of this arrangement will hereafter appear.

The outlet spout 6 communicates with the lower compartment 4 adjacent the wall of the can and extends up, preferably through

the upper compartment, to a point above the level of the upper end of the can, the outer end 7 of the spout being bent for convenience in pouring. This end is provided with a screw cap 8, whereby it may be tightly closed when the can is not in use.

An opening 9 is formed between the two compartments diametrically opposite the opening of the spout 6 into the lower compartment and close to the wall of the container. Preferably a tube 10 communicates with this opening and extends close to the bottom of the compartment. To facilitate the entry of air into the compartment 4, when liquid is being dispensed from the can, I provide an air tube 12 which extends from the mouth of the end 7 of the spout 6 substantially to the bottom of the compartment 4 diametrically opposite the outlet of the spout 6 from the said chamber. Preferably this air tube extends through the tube 10. To facilitate the escape of air from the compartment 4, when the latter is to be refilled with the liquid from the compartment 3, I provide an air tube 11, which opens through the partition 2 adjacent the opening 9, and extends up to a point within the air space at the upper end of the compartment 3.

The operation of the device is substantially as follows: A cap 13, which normally closes the filling tube 5, is removed, and liquid poured into the container until the lower end of the filling tube is sealed thereby. The cap 13 is then replaced. When a receptacle is to be filled the cap 8 is removed. At this time the lower compartment 4 is, of course, full, as well as the upper compartment, the air from the lower compartment having escaped through the tube 11 as liquid flowed down through the tube 10. The air tube 12 and the spout 6 are also full to the level of the lower end of the filling tube 5. When the can is tilted to the position shown in Fig.

2, liquid tends to flow from the lower compartment 4 through the spout, but none can issue from the end 7 of the spout until the liquid contained in the tube 12 has been sucked back into the lower compartment and air is entering the said compartment through the said tube 12. This takes an appreciable length of time, enabling the end 7 of the spout to be inserted in the receptacle before any drip occurs therefrom. When the can is filled, the air at the upper end of

the can, of course, flows to the side which is now uppermost, so that the liquid level in the compartment 3 falls below the level of the opening 9, thus no liquid will flow from the compartment 3 to the compartment 4 when the can is tilted. I thus insure that, when the can is tilted, only the contents of the lower chamber will be dispensed. The device may thus be used to measure and dispense a given quantity of liquid with sufficient accuracy for ordinary purposes.

If less than the quantity contained in the compartment 4 is required to fill the receptacle, the flow can be stopped when the receptacle is sufficiently full by immersing the end of the spout 6 in the liquid in the receptacle, thus closing the end of the air tube 12. The can may then be quickly tilted back to its normal position.

If more than the quantity contained in the lower compartment 4 is required to be dispensed, it will be necessary to tilt the can back to the upright position when the compartment will again fill.

From the above description, it will be seen that I have devised a can which will satisfactorily attain the objects of my invention set out in the preamble to this specification.

What I claim is:—

1. A dispensing container divided by a transverse partition into an upper and a lower compartment communicating with one another only at a point adjacent the wall of the container by means of a tube extending down to a point adjacent the bottom of the lower compartment; and an air tube connecting the upper parts of the two compartments adjacent the side thereof which is uppermost when the container is in dispensing position.

2. A dispensing container divided by a transverse partition into an upper and a lower compartment communicating with one another only at a point adjacent the wall of the container; and an air tube connecting the upper parts of the two compartments adjacent the side thereof which is uppermost when the container is in dispensing position.

3. A dispensing container divided by a transverse partition into an upper and a lower compartment communicating with one another only at a point adjacent the wall of the container by means of a tube extending down to a point adjacent the bottom of the lower compartment; a spout communicating with the lower compartment substantially diametrically opposite the communication aforesaid and extending above the upper end of the container; and an air tube extending from the mouth of the spout to the interior of the tube aforesaid and means for permitting air to enter the upper compartment and to escape from the lower compartment while the latter is filling.

4. A dispensing container divided by a transverse partition into an upper and a lower compartment communicating with one another only at a point adjacent the wall of the container; a spout communicating with the lower compartment substantially diametrically opposite the communication aforesaid and extending above the upper end of the container; an air tube extending from the mouth of the spout to the interior of the lower compartment adjacent the side thereof which is uppermost when the container is in dispensing position; and an air tube connecting the upper parts of the two compartments.

5. A dispensing container divided by a transverse partition into an upper and a lower compartment communicating with one another only at a point adjacent the wall of the container by means of a tube extending down to a point adjacent the bottom of the lower compartment; a spout communicating with the lower compartment substantially diametrically opposite the communication aforesaid and extending above the upper end of the container; an air tube extending from the mouth of the spout to the interior of the tube aforesaid; and an air tube connecting the upper parts of the two compartments.

Signed at Toronto, Canada, this 27th day of September, 1923.

EDWARD DEVINE RANCK.
